UNITED STATES PATENT OFFICE.

DAVID BASCH, OF NEW YORK, N. Y.

HOSE-SUPPORTER.

SPECIFICATION forming part of Letters Patent No. 674,895, dated May 28, 1901.

Application filed January 29, 1901. Serial No. 45,211. (No model.)

To all whom it may concern.

Be it known that I, DAVID BASCH, a citizen of the United States, and a resident of New York city, State of New York, have invented 5 certain new and useful Improvements in Hose-Supporters, of which the following is a specification.

My invention relates to an improvement in hose-supporters of that class wherein the supporter is detachably engaged with the corset and is designed to overcome certain existing defects and to provide a more convenient and secure device for the purpose set forth. It has been the practice to fasten the supporters 10 to the corset generally in two ways—by pinning the supporters to the body of the corset and by uniting the upper ends of the supporters to a pad or hanger-piece provided with means for detachably engaging the same with 15 some part of the corset-clasp. The former method is apt to tear the covering of the corset and is inconvenient for ready disengagement. The devices heretofore produced for carrying out the latter method render accidental dis- 20 engagement from the corset-clasp an unpleasant possibility, are necessarily disengaged from the corset whenever the latter is removed by the wearer, and are generally of a rigid construction, cutting and eventually destroying 25 the portion of the corset-clasp with which it engages. All of these difficulties are obviated by my invention, by which I provide an attaching device having means for detachably engaging the eyepiece of the corset-clasp 30 springing tightly to the same, and when in place impossible of accidentally becoming unfastened, while at the same time the hose-supporters have a free movement in every direction without danger of becoming loos- 35 ened.

Another feature of my invention is the providing of means for more satisfactorily adjusting the strains on the fabric of the stockings than heretofore. This part of my in- 40 vention will be more fully set out hereinafter.

In the following specification, with reference to the accompanying drawings, I have described a structure embodying my invention, the features of the same being more par- 45 ticularly pointed out hereinafter in the claims.

Figure 1 is a view of the lower portion of a corset, parts being broken away, showing

my improvement attached thereto in opera- 5 tive position. Fig. 2 is a similar view show- 6 ing my improvement in place on the eyepiece of the corset-clasp, the corset being unfas- 7 tened. Fig. 3 is a rear view of the attach- 8 ing device on an enlarged scale. Fig. 4 is a 9 sectional view of the parts shown in Fig. 3 10 along the line X X.

a a is an ordinary supporting-tape pro- 15 vided with means *b b* for adjusting the length and depending tapes *c c*, the latter having 16 depending therefrom the bifurcated tapes *d d*, 17 provided with means *e e e e* for attaching the 18 same to the stockings. The tape *a a* is prefer- 19 ably of one piece, passed through the loop *f*, 20 the two portions of the tape being fastened 21 together by a line of stitches at *g*, where they 22 cross each other. Connecting the two portions 23 of the tape *a a* a little below the loop *f* is a 24 stiffening-piece *h*, adapted to hold the two 25 portions of the tape apart and to keep them in 26 proper relation with each other. The tapes *d d* 27 are preferably of one piece, fastened to the 28 tapes *c c* in such manner that they spread apart 29 at a comparatively wide angle, so that the 30 means *e* may grasp the stockings at the sides 31 instead of in the front, as heretofore, thus 32 more widely distributing the strain and less- 33 ening the possibility of tearing the garment. 34 The loop *f* is pivotally connected at *i* with 35 the plate *j*, having the slot *k*. On each side 36 of the slot are guideways *l l*, adapted to slide 37 upon and spring to or grasp tightly the edges 38 of the eyepiece of the corset-clasp in such 39 fashion that the slot of plate *j* will register 40 with the eye of the corset-clasp. The plate 41 *j*, with the depending apparatus, is normally 42 kept in place on the eyepiece of the clasp 43 even when the corset is removed, but may 44 readily be detached by a sidewise pull. When 45 in use, the stud of the clasp is passed through 46 the eye in the ordinary way and also passes 47 through the slot in the plate *j*, the head of 48 the stud bearing against the head of the plate, 49 thus rendering accidental disengagement im- 50 possible. It is obvious that while the plate 51 is rigidly held upon the clasp the pivotal con- 52 nection at *i* with the loop *f* gives a sidewise 53 freedom of movement, while the loop permits 54 a backward-and-forward movement to the 55 tape, which is passed through it, the combi- 56 nation forming a comparatively universal 57

movement subject to every strain without disturbing the rigid connection between the plate and the clasp.

Having described my invention, what I claim, and desire to secure by Letters Patent, is—

1. An attaching device for hose-supporters comprising a transversely-slotted plate adapted to be detachably engaged with the eye-piece of a corset-clasp and pivotally-connected dependent means adapted to receive the supporting means of the supporter.
2. An attaching device for hose-supporters comprising a slotted plate provided with guideways and adapted to slide upon and be detachably engaged with the eyepiece of a corset-clasp and pivotally-connected dependent means adapted to receive the supporting means of the supporter.
3. In a hose-supporter the combination with a garment-supporting tape of a loop through which said tape is adapted to pass, said loop being pivotally connected with a transversely-slotted plate provided with means for detachably engaging the same with the eyepiece of a corset-clasp, the slot in the plate registering with the eye of the clasp.
4. In a hose-supporter the combination with garment-supporting tapes of a stiffening-strip adapted to hold the tapes in a fixed relation to each other, a loop above and separate from the stiffening-strip through which said tapes

are adapted to pass, said loop being pivotally connected with a transversely-slotted plate provided with means for detachably engaging the same with the eyepiece of a corset-clasp.

5. In a hose-supporter the combination of a supporting-tape, having a second depending tape adjustably connected therewith provided with bifurcated means having hose-attaching clasps adapted to bring the clasps to the top of the stocking at the sides, with a transversely-slotted plate adapted to be detachably engaged with the eyepiece of a corset-clasp said plate having pivotally-connected dependent means adapted to receive and hold the supporting-tape substantially as described.

6. An attaching device for hose-supporters comprising a transversely-slotted plate adapted to be detachably engaged with the eyepiece of a corset-clasp, the slot of the plate registering with the eye of the clasp, and pivotally-connected dependent means adapted to receive the supporting means of the supporter.

In testimony whereof I have hereunto signed my name in the presence of two subscribing witnesses.

DAVID BASCH.
